UNITED STATES PATENT OFFICE.

JUSTIN W. GRIESS, OF CINCINNATI, OHIO.

DESIGN FOR LEATHER OR SIMILAR ARTICLE.

Application filed July 17, 1926. Serial No. 18,391. Term of patent 14 years.

To all whom it may concern:

Be it known that I, JUSTIN W. GRIESS, a citizen of the United States, residing at Cincinnati, in the county of Hamilton and State of Ohio, have invented a new, original, and ornamental Design for Leather or Similar Article, of which the following is a specific-

The single figure of the drawing is a plan view of a small section of leather having my new design printed thereon, it being understood that the design is repeated to cover any desired area of the goods.

I claim:

The ornamental design for leather or similar article substantially as shown.
